UNITED STATES PATENT OFFICE

JOHN W. O'NEILL, OF CHICAGO, ILLINOIS

RADIUM EMANATOR

Application filed September 16, 1927. Serial No. 219,850.

My invention relates to means for administering radium emanation and involves a construction whereby practically the entire emanation resulting during each opening and air admitting period of operation will be administered to or obtained by the user with each withdrawal or inhalation and as a result more uniform quantities of the radium emanation is obtained in keeping with the prescribed doses.

The invention also has for its object the provision of a construction whereby the radium element is prevented from contact with outside air and escape of the radium prevented while the device is not in use.

The invention also contemplates a construction which will permit an increased quantity, or dose of greater strength, to be administered with each inhalation or withdrawal.

The objects and advantages of my invention will be readily comprehended from the detailed description of the accompanying drawing, wherein—

25 Figure 1 is a sectional view of my improved emanator shown in condition for use; the withdrawal tube and water-holding vessel or glass being only partially shown.

Figure 2 is a detail sectional view taken 30 on the line 2—2 of Figure 1 looking in the direction of the arrows.

Figure 3 is a sectional view of the device,—with a portion in elevation and the withdrawal tube broken away,—and provided with an auxiliary emanation administering portion.

40 My invention relates to a device intended for administering the emanation of radium in conjunction with a given quantity of pure water or other media; the device being such that the air, before entering and passing about the radium element, when the device is in operation, is made to pass through a suitable air purifying medium in advance of its 45 contact with the radium element and therefore in advance of the emanation coming into contact with the water or other fluid media with which the same are administered.

50 In the specific exemplification of the invention as disclosed in Figure 1, the device

comprises a casing or housing 10 of any suitable configuration and cored to receive a plug-valve 11. In the device as illustrated, the plug-valve 11 is preferably of the tapered type having the threaded stud 12 disposed 55 through one side wall of the casing 10 in order to receive the nut 13 whereby the valve is held in place and at the same time its proper fitting relation with the casing 10 maintained. The opposite end of the plug-valve 11 has an 60 externally threaded extension 14, which receives a suitable hand-wheel or controlling member 15 whereby the plug-valve may be rotated. This plug-valve 11 is provided with suitable ducts which, when the valve is 65 rotated, are intended to be brought into registration with the respective ports in the casing 10. The hand-wheel 15 may be secured to the extension 14 in any suitable manner, for example by means of the set-screw 16. The 70 internally threaded hub portion of the hand-wheel 15 is shown surrounded with a coil spring 17; one end whereof is secured in the side of the casing 10 as shown at 18, while the other end of the spring is secured to the hand-wheel at 19. It is obvious with this construction that the hand-wheel 15 will automatically return to its normal position (which constitutes the closed position of the valve) 75 when the operator releases the hand-wheel. In order to prevent improper contact with the coil spring, I prefer to employ the enclosing cylindrical shell or collar 20 which, however, may be omitted if desired. 80

The plug-valve 11 is cored longitudinally from one end thereof to a predetermined extent in order to provide a chamber 21 within the valve. The inner end of the chamber 21 communicates with a duct 22, at the inner end 90 of the plug-valve, which connects with a port 23 and which in turn, when the valve is in open position, communicates with a port 24 in the casing 10. The chamber 21 in the plug-valve is intended to hold the radium element, generally indicated at 25, which is preferably placed in a wire mesh capsule or container as shown in Figure 1. 95

The chamber 21, at an intermediate point, is internally threaded to receive a closure plug or screw 26 whereby the radium element is 100

held within the inner end of the chamber 21, intermediate of the duct 22 and the plug or screw 26 and therefore normally out of contact with air.

5 The plug-valve 11 is provided with a port 27 which enters the chamber 21 forward of the closure plug 26. The port 27 in turn is intended to register with a port 28 in the casing 10 when the plug-valve has been 10 properly turned to open position.

The casing 10, about the port 28, is counter-bored to provide a pocket 29, which, in Figure 1, is shown provided with a suitable air filtering element, such as asbestos, wool, cotton, or the like, indicated at 30, which is preferably placed intermediate of the wire-mesh or perforated discs 31; the discs and air purifying element being held in place by a suitable washer 32 screwed into the threaded 20 counterbore; the washer being provided with a central opening to permit passage of air therethrough.

The port 24 in casing 10 is provided with a tube 33; and the casing is provided with a 25 counter-bore encircling the port 24 and tube 33 for the purpose of receiving the large tube 34 shown threaded into the counterbore in order to permit assembly and removal. The large tube 34 is preferably longer than tube 33 and has its lower end provided with a suitable check-valve 35 for normally closing the inlet port 36 in the closure member and valve housing 37 and thus prevent discharge or radon through the lower end of the tube.

25 The casing 10 at one side of the plug-valve 11 is shown provided with a duct 38 extending therethrough; the lower end of the duct communicating with tube 34 while the upper end of the duct is provided with withdrawal tube 39 (see Figure 2); a portion of this tube being preferably flexible or of rubber to permit the same to be taken into the mouth of the user for the purpose of withdrawing,—by means of suction,—the liquid or water and resultant radium emanation.

When the device is not in use, the spring 17 will rotate the plug-valve 11 in such direction that ports or ducts 23 and 27 will be out of register with ports 24 and 28, respectively, 50 and as a result air cannot enter chamber 21 and come into contact with the radium element indicated at 25, hence no emanation can be emitted because no withdrawal can be made from the inner end of the chamber 21.

55 When the device is intended to be used, the lower end of tube 34 is inserted into a glass or suitable vessel 40, containing water or other proper media; the free end of tube 39 is placed in the user's mouth and plug-valve 11 is rotated by turning hand-wheel 15 so as to bring port 23 into register with port 24 and port 27 into register with port 28. Suction on the tube 39 will cause air to flow upward through the purifying or air filtering element 30, thence through ports 28 and 27

into chamber 21, allowing it to pass about the radium element 25, out through duct 22, ports 23, 24 and tubes 33 into the immersed, fluid holding end of tube 34. The suction will cause check-valve 35 to move upward off its seat, causing the liquid from the vessel or glass 40 to pass upward into tube 34 into contact with the radium emanation and to be charged thereby; the emanation holding fluid then passing upward through duct 38 and out through tube 39. As soon as the user has taken the requisite quantity and releases hand-wheel 15, spring 17 will rotate plug-valve 11 in the reverse direction back to normal condition where ports 23 and 27 will be out of register with ports 24 and 28, respectively; while check-valve 35, which is held in the closure member 37 by perforated cap 41, will drop to its seat. The check valve 35 is employed to prevent loss or passage of the emanation into atmosphere and the take-off tube 39 is also preferably provided with a check valve as at 39^a to prevent improper use.

90 In Figure 3 I show my improved emanator provided with an auxiliary radium element holding receptacle intended to be employed when the user is to receive a double strength dose as it were, namely where a greater quantity of emanation is to be taken with each withdrawal than might be obtained from the quantity of radium held within the chambered valve of the main casing as described in connection with the construction shown in Figure 1. The construction disclosed in Figure 3 shows the casing 10 having the plug-valve 11, which is identical with that disclosed in Figure 1 and controlled by the hand-wheel or grasp 15. The casing 10, as previously described, is provided with the ducts or ports 24, 28 and 38 (the latter not shown); the latter duct establishing communication with the large outer tube 34 which is intended to be inserted into a liquid-holding vessel or glass; said tube 34 encloses the small tube or stem 33 which communicates with outlet port 24 in the casing and which is intended to have communication with port 23 in the plug-valve 11 when the latter is properly rotated. Such rotation of the plug-valve will cause the port 27 in the valve to be brought into register with the port 28 in the casing. The valve 11 in Figure 3 is shown in closed position. The inner tube 33, as shown in Figure 1, is purposely shorter in length than outer tube 34, so that when outer tube 34 is inserted in the liquid or water in vessel 40, the emanation discharging through tube 33 will pass into the fluid or water which has entered tube 34, and be entrained with the fluid, as the emanation will rise toward the upper end of outer tube 34 when the device is in use. As a result, the user will receive all of the emanation when the valve 11 has been turned to open position.

Where an additional or auxiliary supply of radium is to be administered, the enlarged counterbore 29 about port 28 receives the threaded nipple 42 of a casing 43. Before the nipple 42 is screwed into the counterbore 29, the filtering element with the disc 31 and washer 32 are removed. The casing 43, which may be of any suitable configuration, is shown provided with an annular flange 44 on the lower side and externally threaded to receive the cylinder 45 shown internally threaded at the upper end. The casing 43 is formed to receive a plug-valve 46, controlled by the handle or lever 47; the valve being preferably tapered and secured in place by the nut 48 at the opposite or small end thereof. The plug-valve is provided at predetermined points with ports 49 and 50 extending therethrough. The port 49 is intended to be brought into register with an air inlet duct 51; while port 50 is intended to be brought into register with outgoing duct 52. Where the auxiliary emanator is employed, the air inlet duct 51, which is shown provided with an enlarged or counterbored orifice, is provided with the air filtering element 30. The lower end of the duct 51 is shown provided with a tube 53 which extends into the bottom of receptacle 45; and the duct 52 at its lower end is shown provided with a tube 54 extending into receptacle 45. It will be understood that the plug-valve 11 is chambered as shown in Figure 1 and may be provided with the radium as shown at 25 in Figure 1. The side of receptacle 45 is shown provided with a lug or teat 55 adapted to engage in a socket in the lower end of handle 47 to frictionally hold the latter with the valve in inoperative or closed position.

When the device is used, handle 47 is oscillated to rotate the valve 46 into a position where its ports 49, 50 are brought into register with ducts 51 and 52; hand-wheel 15 is then rotated so as to bring ports 23 and 27 of plug-valve 11 into register with ducts 24 and 28, respectively. As duct 28 of casing 10 is in register with the duct 52 of casing 43, it is apparent that communication will be established with auxiliary vessel 45. The user then places the outer tube 34, which may be termed the mixing chamber, into a vessel containing the desired fluid and upon inducing suction in the device, causes the air to pass through the filter 30, down through tube 53 and up through tube 54 and into the chamber of valve 11. This causes the emanation resulting from the radium in the auxiliary receptacle 45 and from the radium 25 in valve 11 to pass down through inner tube 33 and discharge into large outer tube 34 and with the fluid from the vessel 40 to pass up through duct 38 out through tube 39.

I have shown what I believe to be the best embodiment of the invention, and have described the same in terms employed merely as

terms of description and not as terms of limitation as modifications may be made without departing from the spirit of my invention.

What I claim is:

1. A radium emanator comprising a ported housing, one of said ports being an air admitting port, a second being a discharge port, while a third constitutes a take-off port, a plug valve in said housing adapted to establish communication between the first two ports, said valve having a radium holding chamber intermediate of and communicating with its ports whereby the ingoing air is caused to pass about the radium and discharge its emanation through said second port of the housing, and a pair of tubes, one of which connects with said discharge port while the other tube communicates with said take-off port of the housing, the last mentioned tube having a fluid admitting inlet. 70 75 80 85

2. A radium emanator comprising a cored housing provided with spaced ports leading to the cored portion of the housing, a plug-valve rotatable in said cored portion and provided with a radium holding chamber having ports at opposite ends adapted to register with the ports in the housing when said valve is rotated, air purifying means secured to one of the ports in the housing, a discharge tube secured to the other port in the housing, and withdrawal means arranged to establish communication with said discharge tube; and means whereby said valve is normally rotated to port closing position. 90 95 100

3. A radium emanator comprising a housing provided with an intake port and an outlet port, air purifying means at the orifice of the intake port, a plug-valve rotatable in the housing and provided with ports adapted to register with the ports of the housing, said valve having a radium holding chamber intermediate of the ports thereof and in communication therewith, a tube connected with the outlet port of the housing, a second tube disposed about the first tube, one end of said tube being secured to the housing, a withdrawal tube communicating with the interior of said second tube. 105 110 115

4. A radium emanator comprising a housing provided with an inlet port, an outlet port and a take-off port, a hollow radium holding valve rotatable in the housing and provided with ports adapted to register with the inlet port and the outlet port of the housing, means whereby said valve is normally held in closed position, and a pair of tubes arranged one within the other, the inner tube being secured to the housing at the outlet port, while the outer tube is disposed about the take-off port. 120 125

5. A radium emanator comprising a casing having a longitudinal valve-chamber and spaced ports communicating with opposite ends of the chamber, a chambered radium holding plug seatable in said valve-chamber 130

- and having ports adapted to be brought into register with the ports of said casing, a closure for said radium holding chamber, means for normally holding the plug-ports out of register with the casing ports, an inner tube connected with one of said casing ports, an outer tube of greater length and diameter than said inner tube adapted to receive the emanation discharged from the inner tube, and a withdrawal tube communicating with the upper end of said outer tube.
6. A radium emanator comprising a casing provided with a plurality of ducts communicating with the casing interior at spaced points; one of the ducts constituting an air admitting duct, air filtering means at the orifice of said air admitting duct, means for controlling passage through said ducts, a discharge tube secured in the other of said ducts, a second tube surrounding said first tube and adapted to receive the discharge of the first tube, the upper end of said second tube communicating with a third duct in said casing, and a suction tube secured to the opposite end of said third duct.
15. A radium emanator comprising a casing provided with a plurality of ducts, at spaced points, one of the ducts constituting an air admitting duct, air filtering means at the orifice of said duct, a plug-valve rotatably mounted in the casing and provided with ports adapted to be brought into register with certain of said ducts, said plug-valve having a chamber extending lengthwise and communicating with the ports thereof, said chamber constituting a radium holding chamber, removable closure means for one end of said chamber, a discharge tube secured in a second duct, a second tube surrounding said first tube and adapted to receive the discharge of said first tube, the upper end of said second tube communicating with a third duct in said casing, and a suction tube secured to the opposite end of said third duct.
20. A radium emanator, comprising a casing formed to provide a chamber having spaced ports communicating therewith, one of said ports constituting an air intake port, air purifying means at the orifice of said port, means whereby egress through said air admitting port is prevented, a valve for simultaneously controlling said ports, an outlet tube connected with one of said ports, an enclosure for said tube extending therebeneath and provided in its lower end with a check valve, and a take-off suction tube arranged in communication with said enclosure.
25. A radium emanator comprising a casing having a chamber and spaced ports communicating with said chamber, one of said ports constituting an intake port while the other constitutes an outlet, a valve for simultaneously controlling said ports, an outlet tube connected with said outlet port, a second tube about the outlet tube and extending

therbeneath, the bottom of said second tube having a check valve, a take-off tube connected with said second tube, in combination with a second ported casing removably secured to the intake port of the first mentioned casing with one of the ports of said second casing communicating with the intake port of the first casing, the other port of said second casing constituting an air intake port, a radium holding receptacle removably secured to said second mentioned casing and provided with tubes connecting respectively with the ports of said casing, and valve mechanism for controlling the ports of said second mentioned casing.

10. In a radium emanator, a radium holding receptacle, closure means for the receptacle comprising a casing having ducts extending therethrough, one of said ducts constituting an air intake duct while the other constitutes an outlet duct, each of said ducts at their lower ends being provided with tubes extending into the receptacle, a rotatable plug-valve mounted in said casing adapted to simultaneously control both of said ducts, and air filtering means secured about the orifice of the air intake duct.

11. A radium emanator, comprising a casing having a chamber with spaced ports extending to the casing exterior, one of said ports constituting an air intake port and the other constituting an outlet port, a valve in said chamber for simultaneously controlling said ports, said valve being provided with a radium holding chamber, opposite ends whereof have ports adapted to register with said intake port and with said outlet port, means whereby said valve is normally held in port closing position, air purifying means removably secured at the orifice of the air intake port, a tube secured to the outlet port, a second tube of larger diameter and length disposed about the first tube, said second tube having its lower end normally closed by a check valve, and a take-off suction tube arranged in communication with said second mentioned tube.

12. A radium emanator, comprising a casing having a chamber with spaced ports extending to the casing exterior, the orifice of the intake port being enlarged and internally threaded, a chambered radium holding valve for simultaneously controlling said ports and having ports at opposite ends of the chamber adapted to register with certain of the casing ports, an outlet tube secured to one of said ports of the casing, a second tube of larger length and diameter disposed about the first tube, with one end secured to said casing while the lower end is closed with a check valve, a duct in said casing communicating with the upper end of said second tube, a suction tube communicating with the other end of said duct, in combination with an auxiliary radium holding receptacle, the up-

per end whereof is provided with a closure member having ducts extending therethrough, one of said ducts terminating in a threaded nipple adapted to screw into the threaded orifice of the intake port of the first mentioned casing, a valve mounted in said closure member adapted to control both of said ducts.

13. A radium emanator comprising a casing having a chamber with spaced ports extending to the chamber exterior, one of said ports constituting an air intake while the other constitutes an outlet port, a ported hollow valve, adapted to hold a radium element mounted in said chamber for simultaneously controlling both casing ports, an outlet tube secured to the outlet port of the casing, a second tube of greater diameter and length disposed about the first tube with one end secured to said casing while the lower is closed by a check valve, a suction tube arranged in communication with the upper end of said second mentioned tube, and removable means secured at the inlet port of said casing for filtering the ingoing air.

CERTIFICATE OF CORRECTION.

Patent No. 1,853,282.

Granted April 12, 1932, to

JOHN W. O'NEILL.

It is hereby certified that error appears in the printed specification of the above numbered patent requiring correction as follows: Page 3, line 113, claim 3, for the word "table" read tube; and that the said Letters Patent should be read with this correction therein that the same may conform to the record of the case in the Patent Office.

Signed and sealed this 17th day of May, A. D. 1932.

(Seal)

**M. J. Moore,
Acting Commissioner of Patents.**
